UNITED STATES PATENT OFFICE.

RALPH V. SAGE, OF PHILADELPHIA, AND RALPH E. WILDER, OF JOHNSTOWN, PENNSYLVANIA.

CAR-DOOR.

1,204,692.

Specification of Letters Patent.

Patented Nov. 14, 1916.

Application filed February 4, 1916. Serial No. 76,106.

To all whom it may concern:

Be it known that we, RALPH V. SAGE, residing at Philadelphia, county of Philadelphia, and RALPH E. WILDER, residing at Johnstown, county of Cambria, both in the State of Pennsylvania, citizens of the United States, have invented certain new and useful Improvements in Car-Doors; and we do hereby declare the following to 10 be a full, clear, and exact description of the invention, such as will enable others skilled in the art to which it appertains to make and use the same.

Our invention relates to the construction 15 of car doors with particular reference to metallic doors used on dumping cars; to forming the doors of pressed steel in a particular way to minimize the amount of material used for stiffening and strength- 20 ening the same; in utilizing the door spreaders for adding to the rigidity thereof without the use of unnecessary and extraneous parts, thereby also lightening and cheapening the construction; and to other 25 items as will hereinafter appear.

Referring now to the annexed sheet of drawings which forms part of this specification;—Figure 1 is a vertical longitudinal sectional elevation through a portion of a 30 hopper bottom car taken on the line I—I of Fig. 2; Fig. 2 is a vertical transverse sectional elevation taken on the line II—II of Fig. 1. Fig. 3 is a vertical longitudinal sectional elevation on a larger scale, illus- 35 trating the manner of attaching the links to the spreader bars and the spreader bars to the doors, the left hand section of this figure being taken in front of the clevis member and the right hand section being 40 taken behind the clevis member; Fig. 4 is an elevation and section showing the manner of attaching the links to the spreader bars; Fig. 5 is a detail of the corner portion of one of the doors illustrating the 45 manner of attaching the doors to the spreader bar; Fig. 6 is a detail of the locking pawl and ratchet mechanism for locking the door operating shaft; Fig. 7 is an elevation showing in detail another manner of 50 attaching the links to the spreader bars;

and Fig. 8 is an elevation showing still another manner of attaching the links to the spreader bars.

Referring now to the characters of reference on the drawings:—1 represents the car 55 in general, 2 one of the hoppers at the lower portion thereof, 3 are the doors which are preferably formed of pressed steel in the shape of a shallow pan or box with flanges projecting on all sides thereof. At the forward end of the doors, these flanges are 60 formed upwardly at 4, as illustrated, and substantially in line with or in the same plane as the body or main plate portion of the door. 5 are spreader bars each illustrated 65 as of rolled channel section with upper central portion 6, a pair of web portions 7 and a pair of flanges 8 projecting outwardly from the extremities of the webs, and, for the purpose of economy of 70 design to produce greatest strength and stiffness, the central portion 6 and the flanges 8 are thicker than the webs 7, thereby providing more material at a distance from the neutral axis and making a 75 stronger and stiffer section. By reason of the width of the spreader section in the direction of the flanges 8, this section is also very strong laterally as well as in the direction substantially parallel to the web 80 portions.

The flanges formed on the forward portions of the doors may be omitted, as the door spreaders which are secured to the doors by rivets, as illustrated, may sufficiently stiffen and strengthen this portion. 85

Clevis portions 9, as illustrated, are riveted 90 to the spreader bars by the rivets 10 and provided with an approximately semi-circular bearing portion therein, adapted to receive the ends of the T-bolts 11 which are provided with the threaded shank portions 12, adapted to be screwed into the corresponding threaded sockets 13 which are provided on the ends of the supporting 95 links 14 and 15. The bent upper ends of the links 14 and 15 are indicated as 16 and are provided with pivots 17. A straight link 18 is hinged to this pivot 17 and provided with pivot 19 at its other end, where- 100

by it is connected to the outstanding lug on the sheave 20. The sheave 20 is provided with a groove in its periphery, which groove may be provided with projections adapted 5 to receive the operating chains 21 and 22 which are connected with the smaller winding sheave 23 which is mounted on the operating shaft 24. The end of the operating shaft 24 is provided with a ratchet 10 wheel 25, adapted to be held in position desired by the pawl 26 provided with locking detent 27. The cover plate or central ridge of the car forming a portion of the hopper is illustrated as 28, and extends downwardly to form part of the door jamb. 15

Referring now to the connection between the lifting and lowering links and the door spreader bars, as illustrated in Fig. 7:—29 is a T-bolt with head 30, which is pivotally mounted in the clevis 9, which clevis is secured to the spreader bars 5, which spreader bars are secured to a pair of doors as illustrated. The upper end of this T-bolt or pivot bolt 29 has an upset or enlarged 25 portion 31 provided with an axial cylindrical opening 32 therein, provided with an internal screw. The link in this case is illustrated as 33, formed of a bar of flat steel or other section as desired and has a 30 cylindrical end 34, provided with an external screw-thread which is screwed into the internal thread in the projecting end 31 of the bolt. This provides a simple connection and one which enables the links to be lengthened or shortened as desired, to properly adjust the tight closing of the door. 35

Referring now to the connection of the links to the spreader bar and doors, as illustrated in Fig. 8:—The link 33 is provided 40 with a cylindrical end 34 having an external screw-thread thereon, this being a left-hand thread, while the shank 12 of the T or pivot bolt is provided with a corresponding right-hand thread. These two portions are adjustably connected together by means of the sleeve-nut 35 with internal opening 36, the upper end of the same having an internal left-hand screw thread and the lower end 45 an internal right-hand screw thread to correspond with the portions to which they are secured thereby. In order to adjust the length of the links to properly close the doors in accordance with the construction shown in Fig. 8, this is readily done by turning the sleeve-nut 35 either clockwise 50 or reverse clockwise to lengthen or shorten the links. 55

Referring now to the Figs. 1, 3 and 4:—When it is desired to adjust the doors so 60 that they will close tightly and to allow for wear, slack or deflection of any of the parts, the pin or pivot 17 is withdrawn from the projection on the sheave 20 and from the bent end 16 of the link and the link is turned 65 around its axis to screw or unscrew it as de-

sired on the threaded shank 12, and after this adjustment is made, the link and pin are replaced and secured in position.

The adjustment of the position of the doors and the length of the link corresponding to the illustration of Fig. 7, is accomplished in a similar manner, namely:—The pin 17 is withdrawn, the link 33 with the threaded end 34 is screwed into or out of the internally threaded socket 31 until the length is as desired, whereupon the pin is replaced through the upper end of the link and through the projection on the sheave 20 and secured in position. With the connection of the links to the T-bolts or pivot bolts, as illustrated in Figs. 1, 2, 3, 4 and 7, when the pin 17 is in place, the links cannot rotate nor can the screw-threaded connections move so that an adjustment of this kind once made will not be changed by any jars or vibrations. 80

The adjustment of the lengths of the links of the construction shown in Fig. 8 is made by turning the sleeve nut 35 in either direction as desired, to lengthen or shorten the connection. The adjustment made with the construction shown in Fig. 8 can be easily accomplished at any time without removing any of the parts. 90

By referring to Fig. 2 it will be noted that each spreader bar 5 extends below and is secured to and connects a pair of doors, one on each side of the central longitudinal ridge of the car, the clevis 9 being secured to the spreader bar about midway of its length, while the major portion of the door operating mechanism is located within the hollow central longitudinal ridge of the car. When the doors are in the position as illustrated and it is desired to dump the contents of the car, a wrench is applied to the square end of the shaft 24, the detent 27 turned out of contact with the pawl 26 which is then released from contact with the tooth of the ratchet wheel 25 and the shaft either turned or allowed to turn in such a way that the doors drop down and discharge the load. After this is done the shaft 24 is turned in the opposite direction, thereby winding the chain 21 around the winding sheave 23, causing the sheave 20 to rotate clockwise, as viewed in Fig. 1, whereupon the links 16 are lifted upwardly and their bent ends ultimately rest upon the top of the projection shown on the sheave 20. When the doors are closed the pawl 25 is secured in place against one of the ratchet teeth by the detent 27 which is positioned as shown in Fig. 6. When the doors are closed and locked their weight does not affect the winding 125 chains 21 or the operating shaft 24, but the weight of the doors is sustained directly on the sheave 20 by the bent ends 16 of the links 14 and 15. 120

It should also be noted that the lower 130

ends of the door links 14 and 15 are provided with simple screw-threaded connections to the spreader bar, thereby simplifying and lightening the construction in these 5 respects as compared with other more complicated and heavier devices.

As compared with other constructions, our doors are very simple, with a few number of parts, light in weight, the door 10 spreaders bearing directly against the body or flat plate portion of the door, as illustrated, while the downwardly projecting flanges on the sides of the spreader bars serve to further stiffen the doors and maintain 15 them of proper shape to close and remain tight. The construction of the spreader bars with thicker flanges and top, and with thinner webs is a particular feature of our invention, conducing to lightness, strength and economy.

It will also be noticed that the doors close against the comparatively thin edges of the central ridge cover plate 28 and other similar thin edges of the plate on their other 25 sides so that even should any dust of coal, limestone or other lading adhere to the doors, the doors when closing will cut through this material and seat themselves solidly against the hopper bottom, the metal 30 portions contacting with the necessary tightness.

Although we have shown and described our invention in considerable detail, we do not wish to be limited to the exact and specific details shown and described, but may use such substitutions, modifications, or equivalents thereof as are embraced within the scope of our invention or as pointed out in the claims.

40 Having thus described our invention, what we claim and desire to secure by Letters Patent is:—

1. A dumping car door comprising a plate provided with a flange on each of the sides 45 thereof, portions of said flange on two sides being formed upwardly in line with the door plate, a door spreader resting against the door plate and said upwardly formed flanges and secured thereto.

50 2. A dumping car door comprising a plate provided with flanges on the hinged and side portions thereof, portions of the side flanges being formed upwardly in line with the door plate, and a door spreader resting 55 against the door plate and said upwardly formed flange portions and secured thereto.

3. In a dumping car, a pair of doors each hinged at one of their sides, each of said doors being formed of a plate with integral flanges on the edges thereof, portions of the side flanges being formed upwardly and approximately in line with the door plate, a door spreader resting against each door plate and the upwardly formed flanges 60 thereof and secured thereto, and means se-

cured to said door spreader for raising and lowering said doors as desired.

4. A pair of dumping car doors each composed of a plate provided with flanges on the hinged and side edges thereof, portions 70 of the side flanges being bent upwardly, a door spreader secured within the offset portion so formed, and means secured to said spreaders for raising and lowering the doors.

5. A pair of dumping car doors spaced apart, provided with a door spreader of inverted U-section, with outstanding flanges, the central portion of the section being secured to the body portions of said doors, a 80 clevis secured to the spreader between the doors and adapted to receive a pivoted bolt provided with a projecting threaded shank, a link member provided with an integral internally threaded end adapted to be secured to the threaded shank aforesaid, and means for operating said link members to open and close the doors.

6. A pair of dumping car doors spaced apart, provided with a spreader of inverted U-section with outstanding flanges secured thereto, through its central portion, clevis members secured to the intermediate portion of said spreader and provided with sockets, in which is mounted a pivot bolt provided 90 with an upwardly projecting threaded shank, a link provided with an upset and internally threaded end adapted to receive the screw-threaded shank, and means for operating said link to open and close the 100 doors.

7. A dumping door composed of a pressed pan-shaped plate with flanges on the edges thereof, portions of the side flanges being formed upwardly in line with the body portion of the door, a door spreader resting directly against the up-pressed portions of said flanges and the plate portion of said door.

8. A dumping door composed of a plate with flanges on the edges thereof, portions 110 of the side flanges being bent upwardly, thereby providing a recess in said flanges, a door spreader mounted in said recess and secured to the door.

9. A door spreader comprising a metal 115 bar of channel form with a pair of thin webs each slightly inclined toward the upper connecting portion, and flanges projecting outwardly from the extremities of said webs, the flanges being thicker than 120 said webs.

10. A door spreader section of deep channel section with a pair of comparatively thin webs connected by an integral plate portion, a flange projecting outwardly from the other edge of each web portion, said flanges and plate portion being thicker than 125 said webs.

11. The combination with a pair of car doors of a door spreader secured thereto, 130

comprising a metal bar of channel form, with a pair of webs integrally connected on one side by a central portion and with a flange projecting outwardly from the other extremity of each web portion, said flanges and central portion being thicker than the webs.

In testimony whereof we hereunto affix

our signatures in the presence of two witnesses.
